UNITED STATES PATENT OFFICE.

RICHARD D. HANISH, OF COLUMBUS, OHIO.

MACHINE FOR RENOVATING PICTURE-FILMS.

1,324,350.

Specification of Letters Patent.

Patented Dec. 9, 1919.

Application filed September 22, 1913. Serial No. 791,164.

To all whom it may concern:

Be it known that I, RICHARD D. HANISH, a citizen of the United States, residing at Columbus, in the county of Franklin and 5 State of Ohio, have invented certain new and useful Improvements in Machines for Renovating Picture-Films, of which the following is a specification.

The present invention relates to improvements in machines for renovating picture films, and is especially applicable for cleaning, polishing and renewing the films of moving picture machines.

The primary object of the invention is the 10 provision of a machine to be used in connection with an oiling, washing and cleaning process, in order to polish and renew used films by removing scratched and worn, rough or cracked surfaces due to wear upon 15 the films after they have been used for a considerable time. New films may also be treated and polished by this machine in order to produce thereon a better surface and to lengthen the life of the new film by 20 rendering liability of wear less likely.

In the accompanying drawings I have 25 illustrated one complete example of the physical embodiment of my invention constructed according to the best mode I have 30 so far devised for the practical application of the principles of the invention.

The invention consists essentially in a machine embodying means whereby a film, which has been previously oiled or not as 35 desired, may be unwound from one spool or reel to a second spool and reel, and during the interval of transmission, means are actuated for polishing one or both sides of the film as it moves. Certain other combinations of parts are embodied in the machine such as means for retarding excessive feed of the film from the unwinding 40 reel, and for compensating for increased diameter of the winding reel as the film is 45 wound thereon at the opposite end of the machine.

In the drawings:

Figure 1 is a side elevation of a machine embodying the novel features of my invention.

Fig. 2 is a plan view.

Fig. 3 is a diagrammatic view showing the film passing through the rollers of the machine.

Fig. 4 shows in side elevation one of a plurality of unwinding reels (at the left

of the machine in the drawings) and its support.

Fig. 5 is a plan view of the reel of Fig. 4 showing the journals, supports, and the 60 braking or retarding device for the unwinding reel.

Fig. 6 shows a portion of the reel of Figs. 4 and 5 and particularly a movable supporting arm and its relation to an upright 65 bracket therefor.

Fig. 7 shows in side elevation one of a plurality of winding reels (complementary to the unwinding reels) located at the right end of the machine, the support for said 70 reels being shown in section.

Fig. 8 is a plan view of the reel in Fig. 7, showing a portion of the sectional supporting and operating shaft for the winding 75 reels.

Fig. 9 is a side elevation of a typical supporting roll and its connections showing its relation to the polishing roll.

Fig. 10 is a plan view of the supporting 80 arm and rolls of Fig. 9.

Fig. 11 is a detail view of the unwinding reel of the film oiling device, and Fig. 12 is an edge view of the film oiling device.

In the preferred embodiment of my invention I have shown the operating parts of 85 the machine mounted upon a frame 1, and in the frame are illustrated four large polishing wheels or drums 2, 3, 4, 5, preferably constructed after the manner shown in my Patent No. 1,071,519, issued August 26, 1913, 90 and rotated in the direction of the arrows, in pairs, through their shafts 6, 7, 8, 9 which are journaled in the frame 1. The shafts are all driven from the driving pulley 10 and pairs of gears 11 and 12, the shafts 6 and 7 95 being rotated in the same direction through the wheels 13 and 14 and belt or chain 15. The shafts 8 and 9 are rotated in the same direction through the wheel 16, chain 17, counterwheel 18 on a short shaft 19 in the 100 frame, and the two gears 20 and 21, the former on the shaft 19 and the latter on shaft 8 and the sprocket wheels 61 and 60 on shafts 8 and 9 respectively and chain 62. It will thus be seen that the two drums 2 and 105 3 are simultaneously revolved anti-clockwise, and the two drums 4 and 5 are similarly revolved clockwise. These drums are covered with suitable polishing material and are adapted to polish the film by frictional 110 contact therewith, two drums acting on the upper surface of the film F, shown on Fig.

3 and shown in dotted lines in Fig. 1, and two drums acting on the lower surface as the film passes through the machine. The drums are of considerable width, and in the drawings they are wide enough to polish 5 three films simultaneously, although of course this number may be varied and a larger or smaller number of films may be cleaned at one time, depending upon the 10 width of the drums.

The films pass from left to right in the machine, and as the mechanism for transmitting the film is the same in each case, the process of cleaning one film will be described herein as applicable to all the films 15 and mechanism therefor.

The winding reels are indicated by the numerals 22 and the unwinding reels by the number 23, and these reels are of the usual 20 standard construction for picture films, although of course other reels may be used on the machine with equal facility. These reels are adjustably supported, as will be presently described, to bring the films into 25 contact with different portions of the cleaner structure, so that when one portion is soiled, the film may be readily shifted to a cleaner surface.

In Figs. 4, 5, and 6 the unwinding reels 30 are illustrated in enlarged detail, and it will be seen that they are supported upon two cross bars 24 by means of the movable and adjustable bracket or frame 25 which has perforated ears 26 to slide on the bars 35 and at least one set screw 27 to secure the frame in adjusted position on the bars. The frame is provided with a plurality of uprights or bearing brackets arranged in pairs as 28 and 29, integral with the frame 40 and projecting vertically therefrom. The bracket 28 of the frame is recessed or formed with an open perforation at its upper end to receive the trunnion or journal 30 of the reel, and it is also provided with an arm 45 31 extending to the front and an arm 32 extending to the rear of the reel. The arm 32 is bent as shown and provided with a perforated ear at its end to form part of a hinged joint 33 by means of which the 50 hinged arm 34 is connected to the arm 32. This hinged arm 34 also has an open perforation as 35 for the trunnion or journal 30, and a spring held catch 36 which operates therewith to hold the journal in the 55 recess as will be understood. The two arms 31 and 34 and the front arm 32 embrace one end and the two sides of the reel, and at the front, the perforated ends of the arms 31 and 34 are connected by a bolt 37. The 60 ends of the arms are spaced apart by means of the spring 38 coiled about the bolt and located between the arms, but the arm 34 may be moved toward the reel on its pivot 33 and there held by means of a wing nut 39 on the threaded end of the bolt 37. In

this manner it will be understood that the pivoted arm 34 may be made to swing on its hinge 33 toward or away from the reel, and when swung toward the reel, by turning the nut 39, the arm is made to frictionally 70 engage the reel to retard or brake its movement. To facilitate the movement, the upper end of the bracket 29 has a dovetail slot 40 for the tongue 41 of the arm 34 to slide in, and in this manner the excessive movement of the reel and consequent unwinding 75 of the film is prevented. It will be understood that the frictional engagement of the arms with the reel may be adjusted to suit circumstances by means of the wing nut 80 39, and the unwinding of the film from the reel regulated, and by means of the slidably movable frame 25, the position of the unwinding reels may be laterally adjusted to feed the films to the cleaning or polishing 85 rolls.

The winding reels 22 are supported on cross bars 42, and adjustable frame 43 with its ears 44, may be held in adjusted position by means of the set screw 45, as in the case 90 of the unwinding reels, but the frame is equipped with brackets 46 arranged in pairs and having open upper bearings 47 closed by pins 48. These bearings furnish the support for a specially made, sectional shaft 95 which revolves with the winding reels. The shaft is made up of a plurality of sections 49 upon which a reel is held to rotate by a spline or key 50. At its ends each section is formed with a tongue 51 and slot 52, and 100 in Fig. 8 it will be plainly seen that the tongue and slot connections or joints rest in the open bearings 47 at the upper ends of the brackets 46, and the supported joints thus form a continuous shaft with which 105 the reels, that are keyed thereto, move or revolve, to wind the films from the unwinding reels.

The winding reel shaft which I designate as a whole in Fig. 2, as 53 carries a wheel 110 54 that is revolved from the drum shaft 8 through the medium of the chain 55 and wheel 56, and the clutch 57 operated by handle 58 is employed to connect or disconnect the shaft 53 with its driving means. As 115 the film winds on the winding reel the diameter of the roll on which it is wound increases as will be readily understood and consequently its rate of linear travel is correspondingly increased, while the speed 120 of these films should desirably be kept constant. To compensate for this difference and variation the sprocket wheel 56 is held to revolve with its shaft 9 by a wing nut 59 bearing against spring 59 which is adapted 125 for frictional contact with the wheel, and by means of the nut the spring may be adjusted so that it will allow slipping and lost motion of the wheel 56 as the diameter of the film on the winding reel increases. 130

The shaft 9 is revolved from the shaft 8 through the sprocket wheels 60, 61 and chain 62.

As the films pass through the machine from the unwinding reels to the winding reels, they are supported adjacent the polishing rolls or drums by resiliently suspended rolls as 63, 64, 65, 66. In Fig. 1 it will be seen that the films pass under rolls 63 and 10 66 and over rolls 64 and 65 and that the respective polishing drums are in position for frictional contact with the films as they pass over the rolls, to polish both sides of the films.

15 Referring to the rolls 63 and 66 under which the film passes in Figs. 1 and 2, it will be seen that these rolls are supported each from its respective suspending arm 67, 68, and that the arms are formed with hubs 20 69 that are rotatable on the cross bars or rods 70. By means of a spring 71 the arm 67 is resiliently suspended over the drum 2 and the film as it passes under the roll 63 is thus permitted to have a light contact with 25 the polishing drum. Each arm carries guide rollers 72 that are relatively fixed on the arm, and an adjustable guide roller 73 that is journaled in a pivoted bracket 74 which is urged toward the roll by means of a 30 spring pressed pawl 75, or rather held in position adjacent the roll by said pawl, but a spring 76 tends to pull the roller from the roll. This arrangement is provided so that 35 when the film is being "threaded" through the machine the pawl 75 may be disengaged and the roller pulled away from the roll by spring 76 to facilitate the passage of the film between the roll and roller. There are, of 40 course, three of these suspending arms for each drum, the arms 67 and 68 and their accessories, being identical except that they are arranged to operate on the right and left hand end of the machine respectively, while somewhat similar arms 77 and 78 are arranged in sets to carry the rollers 64 and 65 respectively. A description of the arm 77 in Figs. 9 and 10 will be sufficient to distinguish and identify these devices. The 45 arm is formed with the hub 69 revoluble on the bar 70 and is suspended from the frame by a spring 79 which tends to pull the roller 64 toward the polishing drum 3. Flanged guide rollers 80 and 81 are located at the sides of the roll 64 and these rollers are journaled on the respective brackets 82 and 83 which are pivoted on the arm 77 and connected by a spring 84 which tends to draw the rolls from the roller. The rollers are held in position adjacent the roll however, 50 by means of duplicate pawls 85 which are spring pressed and have hooks 86 to engage in a recess 87 formed in each of brackets. When the film is to be threaded on the machine the hooks 86 are disconnected, and the

spring 84 draws the brackets so that the 65 rollers are withdrawn from the roll and the film may be passed under the rollers and over the roll with facility. It is desirable, although not always necessary that the films be coated with oil before being polished on 70 the machine, and for this purpose an oiling device is positioned at the side of the machine and forms a part thereof. This oiling device comprises an unwinding reel 88 and a winding reel 89, and the unwinding reel 75 is provided with a brake or retarding device to prevent excessive unwinding of the film therefrom. To this end one of the supporting brackets of the reel, as shown in Fig. 11 is provided with a pivoted arm 90 positioned 80 between the forked bracket 91, and the spring 92 between the lower end of the arm and the opposing bracket or post of the reel support tends to urge this lower end outwardly and the upper or journaled end 93 85 is urged into frictional contact with the reel. By means of a winged screw 94 the degree of pressure of the spring may be regulated as will be understood.

The film is moved from the unwinding 90 reel to the winding reel of the oiling device and passes between an oil-coating pair of rollers 95 and 96. The film is coated by the upper roller 96 which receives oil from the tank 97 through the transfer rollers 98, 99, 95 100, the roller 98 being partially immersed in the oil while the roll 100 contacts with upper roll 96. It is necessary to coat only one surface of the film, the upper surface, as it will be understood that when the film 100 is wound upon the winding roller a coating of oil will be transferred from the upper to the under surface of the winding film. The oiling device is operated from the shaft 8 through the medium of the clutch 101, wheel 102, chain 103 and wheel 104, as indicated in Fig. 2, and the winding reel of the oiling device is rotated from shaft 105 of the wheel 104 through wheel 106 and chain 107, and the wheel 108 on the reel shaft 109. A friction device 110 similar to the device 59 is also employed in connection with this winding reel. After the film has been coated with oil, or "oiled" in the oiling device and wound upon its reel, the reel with the film 115 thereon is detached from the winding shaft 109 and is placed on the shaft 30, or rather the shaft 30 is passed through the bearing opening in the reel, and the reel is then suspended by its shaft in the journals as shown 120 in Figs. 4 and 5. After the films are in place on the unwinding reels and the reels located in proper position, the films are successively threaded through the guide rollers and rolls, as described and attached to the winding 125 reels. The driving mechanism is then started, and the films are wound from the reels 23 to the reels 22 as shown by dotted

4
lines and arrows in Fig. 1. The films are designed to move slowly from left to right, alternately under and over the rollers 63, 64, 65, 66, while the large polishing drums 2, 3, 4, 5, which polish opposite sides of the films, move at a relatively greater speed of rotation. The interposition of the two gears 20, 21 (Fig. 2) in the transmission mechanism serves to reverse the direction of the drums 4 and 5, as indicated by the arrows. By the utilization of the rolls on the yielding or resiliently supported arms, the films may be "threaded" through the machine with facility, and the films may be caused to engage the polishing drums with the proper degree of frictional contact to insure most efficient work, which degree of frictional contact may be ascertained by experiment, and the adjustment fixed as desired.

20 By the utilization of the specially constructed sectional winding shaft 53, I am enabled to remove a wound reel at will and substitute an empty reel, without disturbing the remaining reels, by disconnecting the section 49, removing the section and its reel from the shaft and then removing the reel from the section and replacing the section and a new reel on the shaft.

30 Guide rollers 95' may be employed in the oiling device to guide the film to the coating rollers, and it will be understood that the roller 99 which is in a pivoted bracket 99' may be lifted for a time from contact with rollers 98 and 100, if it is found the oil is being fed excessively.

35 The oiling rollers 98 99 100 are revolved while in contact by means of the train of gears indicated in Fig. 2 at A, B, C.

40 The oil referred to which is applied to the film before it is cleaned or renovated may be of various characteristics, and may be changed to suit the conditions existing in the films. It will be noted that the rotary movements of the pairs of drums are in reverse directions and that as a consequence the drums 2 and 3 draw the film to the right while the two drums 4 and 5 tend to retard

the movement, thus equalizing the passage of the film through the machine. 50

Having thus fully described my invention, what I claim as new and desire to secure by Letters Patent is:—

1. A film renovating machine comprising a general framework, a cleaning structure 55 of at least double the width of a film and arranged to come into cleaning contact with a film, a rotatably mounted unwinding reel, a rotatably mounted winding reel, and means for adjustably supporting said reels 60 so that they may be adjusted laterally to bring the film into cleaning contact with different portions of said cleaner structure.

2. A film renovating machine comprising a general framework, a cleaning structure 65 of a width to accommodate a plurality of films and arranged to come into cleaning contact with said films, a plurality of rotatably mounted unwinding reels, a plurality of rotatably mounted winding reels, and means 70 for adjustably supporting said unwinding and winding reels so they may be adjusted laterally to bring the films into contact with different portions of said cleaner structure.

3. A film renovating machine comprising 75 a general framework, a cleaning structure of width to accommodate a plurality of films and arranged to come into cleaning contact with such films, a plurality of rotatably mounted unwinding reels, independent and 80 regulable means for each unwinding reel to retard its free rotary movement, a plurality of rotatably mounted winding reels, means for imparting rotation to said winding reels, and means for adjustably supporting 85 said unwinding and winding reels so they may be adjusted laterally to bring the film into contact with different portions of said cleaner structure.

45 In testimony whereof I affix my signature 90 in presence of two witnesses.

RICHARD D. HANISH.
